(57) **CLAIM**

The ornamental design for a car cup power inverter, as shown and described.

DESCRIPTION

FIG. 1 is a perspective view showing a car cup power inverter.

FIG. 2 is a front view of a car cup power inverter.

FIG. 3 is a rear view of a car cup power inverter.

FIG. 4 is a top view of a car cup power inverter.

FIG. 5 is a bottom view of a car cup power inverter.

FIG. 6 is a side view of a car cup power inverter; and, FIG. 7 is the opposite side view of a car cup power inverter. The broken lines portion of the figure drawings is included to show environmental structure that forms no part of the claimed design.
